REFRIGERATING APPARATUS

Andrew A. Kucher, Dayton, Ohio

Application September 24, 1936, Serial No. 102,368

2 Claims. (Cl. 220—9)

The present invention relates to insulating wall structures and more particularly to insulated cabinets.

Wall structures, to which the present invention is directed, usually include an inner wall or lining and a spaced outer wall. The space between the walls is utilized for insulating between the walls. A frame of low heat conductivity is usually placed between the walls for spacing and supporting the walls. A breaker strip of low heat conductivity is used for covering the space between walls and for covering the frame.

One of the objects of the present invention is to utilize the breaker strip to secure one or more of the edges of the walls to the frame; to utilize the breaker strip to cover the edge as well as secure the edge of the wall in position.

In carrying out the above object, it is a further object to form the edges of the walls into flanges extending toward one another whereby a flat breaker strip can be employed for covering and securing the edges of the walls in position.

Another object is to arrange the parts so that the breaker strip overlies a door seal and thereby holds the latter in position.

A further object is to arrange the door seal so that it covers the joint between the wall and breaker strip.

A still further object of the present invention is to provide an insulating cabinet including an outer casing and an inner lining in which breaker strips are utilized for attaching the frame with the casing and lining and for securing the casing and lining with one another.

Other and further objects and advantages will be apparent from the following description, reference being had to the accompanying drawings wherein a preferred form of embodiment of the present invention is clearly shown.

In the drawings:

Fig. 1 is a perspective view of the improved cabinet;

Fig. 2 is a fragmentary sectional view taken on line 2—2 of Fig. 1;

Fig. 3 is a fragmentary sectional view taken on line 3—3 of Fig. 2;

Fig. 4 is a rear view of the door with parts removed and showing the cover pan and part of the frame in position;

Fig. 5 is a longitudinal sectional view taken on line 5—5 of Fig. 1;

Fig. 6 is a fragmentary view of the frame of the cabinet showing a joint between frame members or posts; and

Fig. 7 is a fragmentary view of the frame of the

door showing a joint between frame members or parts.

The insulating wall structure of my invention may be utilized in many different forms and for illustrative purposes, I have embodied the same in a refrigerator cabinet 20, having door 21 hinged by hinges 22. Sealing strips 23 and 24 seal the joint between the door 21 and the cabinet 20. A suitable latch is disposed within the door and is actuated by a latch mechanism 25.

The walls of the cabinet are in the form of two sheet metal casings, an outer casing 27 and an inner casing or lining 28. These casings are spaced from one another throughout so as to provide an insulating chamber completely around and in back of lining 28. Preferably insulating material such as cork, rock wool or other suitable material 30 packaged in heavy paper or the like, is carried in the insulating chamber. The outer casing 27 is formed of two sheets of metal. One of these sheets is formed to provide the front, the top, the bottom and both sides of the casing. The adjoining ends of the sheet are welded together and the second sheet is also welded to the top, bottom and sides to form the closed back for the cabinet.

The front edges of the top, bottom and sides of casing 27 are bent inwardly to form the front 31, and then rearwardly at an obtuse angle, to form flanges 32. The front edges of the top, bottom and sides of casing 28 are bent outwardly, as at 34, and then forwardly, at an obtuse angle to form flanges 35. Flanges 32 and 35 of the casings 27 and 28 are aligned. A frame 36, comprising four frame members 37, is carried at the front of the cabinet 20 between the casings 27 and 28. Each of these frame members is substantially of trapezoidal shape in cross section and the angling sides thereof abut the flanges 32 and 35 of the casings. Other sides of the frame members each abut the interior of the front portions 31 and the interior of the top, bottom and sides of casing 27. The width of the frame member 37 is such that the rear sides thereof are substantially flush with the rear sides of flanges 34. Thus the rear sides of the frame members and flanges form an abutment for the packaged insulation. The ends of the frame members are undercut as shown in Fig. 6, so that adjoining ends thereof interfit.

In assembling the cabinet, frame 36 is first inserted in position in outer casing 27. If desirable, the frame members 37, can be inserted individually or if desirable, the frame members can be built as a unit and then, by cocking the same, this unit as such is inserted in casing 27. Next

the packaged insulation 30 is placed in position against the interior of casing 27. After all of the insulation is in place, the inner casing or lining 28 is inserted. When in place, the flanges 35 will abut the angling side of the frame member 37.

A breaker strip 42 is then attached to the angling side of each frame member 37 by screws 43. These breaker strips overlie the flanges 32 and 35 and when in secured position, clamp the flanges 32 and 35 in position and form a lock between the frame 36, casings 27 and 28 and breaker strips 42. The holes for the screws 43 are preformed in the frame members 37 and the breaker strips 42 so as to insure positive positioning of the casings 27 and 28 and frame 36 with respect to one another.

It will be seen from the foregoing that I have provided a cabinet which is sturdy and requires merely a few frame members. In this manner, a thick layer of insulation can be placed substantially entirely about the lining 28. Usually the frames for refrigerator cabinets are constructed of wood and in accordance with the present invention, the quantity of wood necessary for frame purposes is minimized. In small capacity cabinets, the bottom of lining 28 can rest directly on the insulation 32, however, in larger capacity cabinets, it may be desirable to support the rear of the lining 28 directly by the outer casing 27. In the latter case, a strip of wood or the like 45, extends across the outer casing 27 and rests thereon and the rear of the lining 28 rests directly on this strip 45.

It will be noted that no screw holes are necessary in either of the casings 27 and 28. The screws for maintaining the parts of the cabinet in locked position are screws 43 and these do not pass through either of the linings. Although screw holes have been eliminated, nevertheless, the cabinet is sturdily constructed and the cause of corrosion, usually incident when screw holes are present, is completely eliminated.

The breaker strips, in addition to locking the casings 27 and 28 and the frame 36 in position, cover the edges of the flanges 32 and 35 and being made of substantially non-heat conducting material, conduct very little heat from one casing to the other. Also, the breaker strips seal the flanges 32 and 35 of the casings 27 and 28 to the frame 36 and, since the casings are otherwise sealed, the insulating chamber between the casings is substantially air tight.

It will be quite obvious that the sealing strips 23 and 24 can be carried either by the door 21 or cabinet 36 or one strip could be carried by the door and one by the cabinet. In the preferred embodiment, I have shown both sealing strips 23 and 24 carried by the door 21 and the construction of the door will now be described. The door 21 includes a sheet metal outer cover in the form of a pan 50 providing a front wall 51. The material is bent rearwardly to form narrow side walls 52 and then inwardly to form rear inwardly extending flanges 53. The portions 51, 52 and 53 form a channel 54 within the outer four edges of the door. A frame 56 is disposed within the door and forms an insulating compartment or chamber. Preferably packaged insulation 57 is carried in the insulating compartment which is covered on one side by the front wall 51 and on the other side by a rear wall or panel 58. This insulation fits snugly against the walls 51 and 58 and against the frame 56.

The frame 56 includes two vertically extending

frame members 61, two horizontally extending frame members 62 and a sub-frame 63. In assembling, the members 61 are first inserted into the opposed vertical sections of channel 54 and then the members 62 are inserted into the opposed horizontal sections of channel 54. The ends of members 62 tightly abut the edges of members 61 so that all of said members are firmly held in the channel sections 54. Then the sub-frame 63 is attached as a unit to the frame members 61 and 62 by a series of long countersunk screws 65 which extend through the frame 63 and into the members 61 and 62. The inside edges of frame 63 and frame members 61 and 62 are flush.

The sub-frame 63 includes four members, namely, the two side and top and bottom members 66 formed from the same cross sectional stock as frame members 37 of the cabinet. The ends of these members 66 are undercut as shown in Fig. 7 so that adjoining ends thereof interfit. Countersunk screws 68 extending through the undercut portions of certain of the members 66 and into certain other of the members secure the members in fixed position to form the frame 63. The panel 59 is secured to the frame 63 by screws 69.

Strip means are provided for covering the exposed portions of the door, which portions are not covered by the pan 50 and panel 51. The strip means include the sealing strips 23, and 24, four breaker strips 71 and four thin cover strips 72, the latter being formed preferably of sheet metal.

The sealing strips 23 and 24 are cut from the same stock and are preferably formed from resilient rubber. The sealing strip stock includes a hollow section 74, which is adapted to resiliently engage the front of the cabinet 20, and two laterally extending sections 75 and 76. These sections are disposed substantially at right angles to one another. The section 75 is L-shaped in cross section and the section 76 is flat. The L-shaped section 75 forms a hook for holding the strip in position. The hook of strip 23 is slid over the extending edges of panel 59 and is held against the edges of the panel by the beveled edges of breaker strips 71. The flat sections or skirts 76 of strip 23 overlie the screws 60. The four frame members 61 and 62 are grooved at 78 to receive the hook section 75 of strip 24. The shank portion of this hook section abuts the edges of the flanges 53 of pan 50. The metal strips 72 are slid into the open end of the hook 75 and the opposite edges of strips 72 are covered and held in place by the beveled edges of breaker strips 71. The skirts 76 of strip 24 conceal the joints between the metal strips 72 and the breaker strips 71. The sealing strips 23 and 24 are each formed from a continuous piece of stock, the skirts 76 being notched to accommodate for the right angle turns of the door.

After the strips 23, 24 and 72 are positioned, the breaker strips 71 are secured by tightening the screws 60 which extend through the breaker strips and into the sub-frame 63. Beveled edges of breaker strips 71 force the shank of hook section 75 of sealing strip 23 tightly against the projecting edges of the panel 59. The inner edges of strips 72 abut the chamfered edges of the sub-frame 63 so that the sealing strip 24 cannot move inwardly and the beveled edges of the breaker strips 71 prevent displacement of strips 72. Thus, the breaker strips 71 secure the entire strip means in position. The holes for screws 60 in the strips 71 and sub-frame 63 and the holes for screws 65 in the sub-frame 63 and frame members

61 and 62 are preformed before assembly so as to insure positive positioning of the assembly.

Thus it will be apparent that the strip means 23, 24, 71 and 72 extends across the space between the pan 50 and the panel 59 and covers and thereby conceals the exposed parts of frame structure which are not covered by the pan and panel. This strip means covers and conceals the joints between the frame structure and the sheet metal pan 50 and panel 59, and the screws 69 for panel 59. This strip means also provides a double seal between the door 21 and cabinet 20. Furthermore, all of these strips are secured in position by merely securing the breaker strips 71 in position.

The breaker strips 71 are formed from the same stock as breaker strips 47 of the cabinet and do not conduct heat readily from the pan 50 to the panel 59. In the cabinet construction, the wider faces of the breaker strips abut the flanges 32 and 35 and in this manner the beveled edges of the strips lie at the proper angle from an appearance standpoint. In the door construction, the narrower faces of the strips abut the sub-frame 63 and the beveled edges thereof are at the proper angle for holding the facing strips 72 and sealing strip 23 in position.

Preferably the sections of the hinges 22 are welded to the front 31 or casing 27 and to the back portion 52 of pan 50 and therefore no screw holes are necessary in the casing 27 and pan 50.

By virtue of the present invention, the construction of the refrigerator and the door therefor has been materially simplified and the number of different stock pieces has been materially reduced. The frame members 37 of the cabinet and the frame members 66 of the door are formed from the same stock. Likewise the breaker strips 47 and 71 are formed from the same stock. The arrangement and construction of the parts are such that the heat leakage is materially reduced.

5 By the present construction two spaced door seals are readily applicable. Sealing strips 23 and 24 are readily applied to the door 21 and abut the surfaces of the front 31 of outer casing 27 and the front 34 of inner casing 28 of the cabinet. The walls of the door 21 and cabinet 20 confining the space between the two sealing strips 23 and 24, being made substantially entirely from low heat conducting material, form 10 a dead air chamber in which minimum circulation takes place.

Thus it is apparent that I have provided a cabinet which is well insulated and can be manufactured at a relatively low cost.

15 While the form of embodiment of the present invention as herein disclosed constitutes a preferred form, it is to be understood that other forms might be adopted, all coming within the scope of the claims which follow.

I claim:

20 1. In an insulated wall structure, a frame member; a cover for the frame; a sealing strip covering an edge of said cover; a second cover for the frame having an edge engaging said sealing strip for holding the latter in place; and a breaker strip attached to the frame member and overlying the second cover for holding the second cover in place.

25 2. In an insulated wall structure, a frame member; a cover for the frame; a sealing strip covering an edge of said cover; a second cover for the frame having an edge engaging said sealing strip for holding the latter in place; a third cover for the frame; a second sealing strip covering an edge of the third cover; and a breaker strip attached to the frame member and engaging the second cover and second sealing strip for holding the second cover and the second sealing strip in place.

ANDREW A. KUCHER.
